WINDLASS.

No. 316,602.

Patented Apr. 28, 1885.

UNITED STATES PATENT OFFICE.

RODNEY F. CARTER, OF SOUTH RYEGATE, VERMONT.

WINDLASS.

SPECIFICATION forming part of Letters Patent No. 316,602, dated April 28, 1885.

Application filed September 25, 1884. (No model.)

To all whom it may concern:

Be it known that I, RODNEY F. CARTER, of 5
South Ryegate, in the county of Caledonia and
State of Vermont, have invented certain Im-
provements in Windlasses, of which the fol-
lowing is a specification.

This invention relates to an improved wind-
lass to be used in the hoisting of stone in quar-
ries and for a variety of other purposes; and
10 it consists in certain details of construction of
the windlass, as will hereinafter fully appear.

In the drawings forming a part hereof, Fig-
ure I is a partly sectional front view of the
windlass; Fig. II, an exterior end view of the
15 same, and Fig. III a plan of the invention with
a portion thereof removed.

A is the platform of the windlass, formed
of the timbers *a*, framed together in any suit-
able manner.

20 B is a frame fastened to the platform A,
supporting the cross-piece C.

D is a revoluble shaft resting in suitable
bearing-boxes, *b* and *c*, the former on the cross-
piece C and the latter on the platform A.

25 E is a head secured to the upper end of the
shaft D, to which is fastened a pole, F, adapt-
ed for the attachment thereto of a horse, as
shown in Fig. I.

G is a differential drum, the larger and
30 smaller sections of which are denoted, respect-
ively, by *d* and *e*. This drum is placed loosely
on the shaft D, and its lower head, which is
protected by a flange, *f*, rests on the bearing-
box *c* on the platform A. The upper head of
35 the drum is provided with a central plate, *h*,
having inclined teeth thereon, and the shaft
D with a clutch, H, having similar teeth,
adapted to engage with those on the plate *h*.

A feather, *i*, serves to communicate the ro-
40 tary motion of the shaft to the clutch, and ad-
mits of the latter device being moved longi-
tudinally of the shaft. The clutch is thrown
in and out of gear with the toothed plate *h* by
means of a lever, *l*, connected by means of
45 pins *m* to a band, *n*, which surrounds the
clutch. The clutch H may be held in an ele-
vated position by a rod, *o*, which is hooked
over the end of the lever *l*, as shown in Fig. I.

I is a friction-band extending partially
around a flange at the base of the drum G, 50
and attached at one end to the platform A.
The other end of the friction-band is connect-
ed to a lever, J, by means of which it may be
tightened on the drum, so as to prevent its
being turned.

55 K is a spiral flange on the upper end of the
section *d* of the drum G, to guide the hoisting-
rope, (not shown,) which is fastened to it, from
one section of the drum to the other.

In loading a truck with stone—one of the 60
many uses to which my windlass may be ap-
plied—the operation is as follows: The shaft
being in revolution, with the winding-rope
extending through suitable snatch and other
blocks to the hoisting-sheaves and made fast 65
to the stone to be raised to a truck, the clutch
is thrown in, which causes the rope to be
wound on the larger section of the drum.
This winding is continued until all the slack
is taken up, when the rope is guided by hand 70
to the spiral flange, and thence automatically
to the smaller section of the drum. By this
transfer the leverage is greatly increased and
the stone elevated without difficulty.

75 When it is desired to lower the stone to the
truck, the brake is first applied and then the
clutch thrown out. The brake is then slack-
ened until the stone causes the drum to re-
volve. The rate of speed of descent is gov-
erned by the power applied to the lever J. 80

I claim as my invention—

In a windlass, a frame-work and a revoluble
shaft supported therein with means to turn
it, combined with a differential drum on the
said shaft, adapted to be turned independently 85
of the shaft, having at its upper end a toothed
plate, a clutch fitted to engage with the said
toothed plate, and a spiral flange between the
larger and smaller sections of the drum, sub-
stantially as and for the purpose specified.

RODNEY F. CARTER.
